Patented Apr. 13, 1920.

Inventor:
Adrian H. Hoyt
by Frank Dooley,atty.

UNITED STATES PATENT OFFICE.

ADRIAN H. HOYT, OF PENACOOK, NEW HAMPSHIRE.

DESIGN FOR A PORTABLE ELECTRICAL MEASURING INSTRUMENT.

54,843.

Specification for Design.

Patented Apr. 13, 1920.

Application filed March 21, 1919. Serial No. 284,216. Term of patent 7 years.

To all whom it may concern:

Be it known that I, ADRIAN H. HOYT, a citizen of the United States of America, residing at Penacook, in the county of Merrimack and State of New Hampshire, have invented a new, original, and ornamental Design for a Portable Electrical Measuring Instrument, of which the following is a specification, reference being had to the accompanying drawing, forming part thereof.

The figure is a perspective view of my improved design for portable electrical measuring instruments.

What I claim is:

The ornamental design for a portable electrical measuring instrument, as shown.

In witness whereof I hereunto subscribe my name this 13th day of March, A. D., 1919.

ADRIAN H. HOYT.
